UNITED STATES PATENT OFFICE.

CONRAD M. CONRADSON, OF MADISON, WISCONSIN, ASSIGNOR, BY MESNE ASSIGNMENTS, TO PRECISION GLASS GRINDING MACHINE COMPANY, OF SIOUX FALLS, SOUTH DAKOTA, A CORPORATION OF SOUTH DAKOTA.

MACHINE FOR SPIRALLY GRINDING INTERCHANGEABLE SPIRALLY-GROUNDED BOTTLE-NECKS AND STOPPERS THEREFOR.

No. 914,243

Specification of Letters Patent.

Patented March 2, 1909.

Application filed May 16, 1906. Serial No. 317,146.

To all whom it may concern:

Be it known that I, CONRAD M. CONRADSON, a citizen of the United States, residing in Madison, in the county of Dane and State of Wisconsin, have invented certain new and useful Improvements in Machines for Spirally Grinding Interchangeable Spirally-Ground Bottle-Necks and Stoppers Therefor, of which the following is a specification.

10 This invention relates to a machine for making interchangeable, spirally ground, (preferably truncated, cone-shaped) interiors of glass bottle-necks and spirally ground, (preferably truncated, cone-shaped) exteriors of glass stoppers therefor.

15 The general object of the invention is to obviate the cumbersome and unduly expensive successive operations of the old art, the final result of which was, and is, the production of ground-glass jointed bottle-necks and stoppers, of which no stopper properly fits any bottle other than the particular bottle with which it was originally mated, and of which no bottle properly fits any other stopper than the particular one with which it was originally mated.

20 The ground-glass joint-forming art, as it relates to bottles and stoppers, has long been, and is, substantially as follows:—The truncated, cone-shaped interior surface of the glass bottle-neck, and the truncated, cone-shaped exterior surface of the glass stopper, whether blown or formed in molds, are initially untrue with reference to the geometrical axis of the truncated cone; that is, to the lengthwise axes of the bottles and stoppers. The said surfaces are also more or less rough; that is, of a more or less irregular, hill-and-dale condition. The first operation 25 in the prior art is to give approximately proper form to the said surfaces. In the case of the bottle-neck, a so-called "lapping" tool rotatably mounted in a machine has been used. This tool is cone-shaped, and 30 generally consists of a wooden core spirally wrapped with sheet iron. The workman with one hand holds the bottle on the free end of the rotating "lap," moving the bottle-neck back and forth on the "lap," longitudinally, while with the other hand he feeds 35 between the "lap" and bottle-neck interior an abrasive mixture. This initial manual "lapping" operation is usually carried on

until the desired quantity of bottle-necks has been "lapped." The stoppers are primarily 55 put in a rotating chuck and roughed out by means of a "lap," generally consisting of a copper-faced strip of wood one end of which is mechanically held, the workman with one hand pressing the free end of this "lap" 60 against the rotating stopper surface while feeding with the other hand abrasive material between the stopper and the "lap." Leaving the stoppers, *seriatim*, in the chuck, the workman takes the bottles, *seriatim*, and 65 holding a bottle, in one hand, with the other hand feeds abrasive mixture between the opposed surfaces of the stopper and bottle-neck, moving the bottle-neck back and forth over the stopper until the joint-forming surfaces of the bottle are mated. On the best 70 grade of work it is frequently the custom to put each stopper in its bottle, after the "lapping" operations and oscillate them in relation one to another by hand to perfect the 75 tightness of joint. In this old art, said surfaces are in fact used as tools for their own production, one surface modifying the other in such wise that there is no reasonable likelihood of interchangeable matability. Consequently, the further practice is to tie each 80 stopper to its own bottle, so as to keep them together for storage and transportation, and for cleaning before shipment. In shipping, it is also usual to insert a bit of paper between each bottle-neck and its stopper, so as to prevent breakage. The jobbers and 85 retailers also have to keep such bottles and stoppers in mated pairs, as received. By the old process, as a general rule, the said 90 surfaces are neither properly round nor straight; and are therefore exceedingly apt to stick together; and the joints are not tight to the proof alcohol test except by careful 95 manual grinding of each stopper in its own bottle. The practical resultant condition of the ground-glass joint art as it relates to bottles and stoppers is that the field of use thereof is comparatively restricted, such bottles and stoppers being unduly expensive and frequently unsatisfactory. It is a fact, moreover, that no one of said surfaces is uniformly 100 finished, each surface being irregular at the best.

The advantages of the present invention 105 are, elimination of the expense of time and

labor of the old manual "lapping operation," and the production of interchangeable bottle-necks and stoppers, which may be shipped separately and used indiscriminately, size 5 for size.

The main factors in the machine herein described for use in making my interchangeable ground-glass bottle-necks and stoppers of the usual truncated cone shape, are a rotatable glass-cutting pencil having a conical working end and a work-holder arranged, one in relation to the other, in such wise that their lengthwise axes are inclined one to the other and to a vertical plane cutting said axes for maintaining the pencil in proper working relation to the truncated cone surface of the glass to be ground; and a controlling mechanism, operable at the will of the operator, to effect one or more uniform, spiral cuttings of the glass surface to be treated. If more than one such cutting is desired, as will be usually the case, the spiral cuttings are preferably to overlie and intersect one another. The longitudinal axes of both the pencil holder and work holder are inclined one to the other and to a plane (indicated in Figure 3 by the dotted line $o-o$) which cuts the longitudinal axes of both the pencil holder and work holder; and that conical surface of the pencil which is in contact with the beveled surface of the work and also the beveled surface of the work itself are in line with one another; that is, in another plane which intersects the plane indicated by the dotted line $o-o$, so that the beveled grinding conical surface of the pencil may contact with the correspondingly inclined surface of the work during each rotation and reciprocation of the conical working end of the pencil.

The described arrangement of the conical working end of the pencil and work, including the work holder and the pencil holder, is wholly new with me, in so far as I am advised.

In the drawings accompanying and forming a part of this specification, Fig. 1 is a side view of a practicable embodiment of a form of the present invention; Fig. 2 is a plan view thereof; Fig. 3 is an enlarged view of one of the work-holders shown on a horizontal plane, and one of the pencil-holders and pencils in plan; Fig. 4 is a longitudinal section of one of the work-holders on a plane in about the line 4-4 of Fig. 5, looking in the direction of the arrow; Fig. 5 is a view in about the line 5-5 of Fig. 4, looking in the direction of the arrow; Fig. 6 is a front view of the work-holder; and Fig. 7 is a section of the work-holder in a plane horizontal to the axis thereof, and at about right angles to the position illustrated in Fig. 3.

The form of machine herein illustrated embodies a frame work having a base portion 10, side members 11 and front member 12,

which form supports for the various parts of the mechanism. Each end of the frame is shown provided with ways 13 upon which a pencil carriage 14 is slidably mounted and upon which pencil carriage any desired number, one or more, of pencil carriers are mounted, each supported by a pair of standards 15, 15, which are set at an angle to the line of reciprocation of the carriage. These standards are provided with suitable bearings in which a pencil-carrier 16 is mounted, which may be driven by some suitable means, as, for instance, a belt 17 driven from a pulley and some suitable source of power, not shown. The pencil-carrier or tool spindle 16 is shown located on a horizontal line and having some suitable form of chuck 18 in which a glass-cutting pencil 19 is mounted. The pencil is preferably of carborundum.

In the present illustration the relative movement between the pencil and the glass to be operated on (here shown in the form of a bottle,) is produced by reciprocating the carriage 14 upon its ways. This in the present instance is done by means of a driver or eccentric shaft 20 driven by means of a pulley 21 from some suitable source of power, not shown. The shaft 20 has fast upon it a pair of eccentrics 21' embraced by eccentric straps 22 connected by eccentric rods 23 to the carriage. The present means of connection are ordinarily for adjusting the place of reciprocation of the carriage 14 on its ways 13, and comprise a shaft 24 mounted in suitable bearings 25 upon the carriage, this shaft 24 being provided with a pair of eccentrics 24' embraced by eccentric straps 23'. Shaft 24 may be rotated by means of a worm wheel 26 fast upon it and meshing with a worm 27 stepped in a bearing 28 in the carriage and controlled by means of a hand wheel 29. By this means the forward and backward limits of the strokes of the pencil or pencils may be regulated, so that after they are individually adjusted and become gradually worn away in use they may be advanced in unison toward the working position by merely rotating the worm 27, and the same advantage obtains if only one pencil is used.

In the present form of machine, the lengthwise axial line or axis of rotation of pencil 19 is at an angle to the right line path of traverse of pencil-carriage 14, this angle being equal to one-half of the contained angle of the frusto-conical surface to be ground; and consequently the effective operation of the machine is to grind the glass into a frusto-conical shape, whether the glass surface to be ground is the frusto-conical interior of the bottle-neck or the frusto-conical exterior of the stopper. But it is to be observed that if the work-holder and tool were mounted so that their axes of rotation were in the same plane, then the surface ground would

be cylindrical instead of conical. In the preferred arrangement, the end 28 of the pencil has a conical point, which shape is automatically maintained by the grinding process, as will be evident from Fig. 3, wherein 29 indicates that part of the slanted surface of the beveled point which is assumed to come first into contact with the glass to be ground, and such surface 29 is at an angle to the 10 axis of rotation of the work-holder. Consequently in the rotation of the pencil, its beveled point is kept true. This automatic formation of the beveled pencil point is of importance in the economic use of the machine 15 in the grinding of the frusto-conical surfaces mentioned. It is to be noted, also, that when the rotating pencil is in contact with the rotating work, the angle between the axes of rotation of the pencil and work or 20 work-holder is always constant.

A convenient means for feeding the work-holder or spindle is illustrated herein, wherein a slide rest 30 is mounted in transverse ways 31 upon the machine frame, and such 25 slide rest 30 is fed cross-wise of the line of reciprocation of the pencil-carriage 14 by means of a rocking lever 32 pivoted to one arm 33 extending from the machine frame, a suitable link 34 connecting the lever to said 30 slide rest. The purpose of this adjustability is to position the pencil and work-holder one in relation to another so as to bring the pencil and glass together for grinding. The other end of the lever carries a roll 35 which 35 runs in a cam groove 36 of a wheel 37, which wheel is carried by a shaft 38 having fast upon it a worm wheel 39 in mesh with a worm 40 upon the shaft 20, and driven in the present instance by means of a pulley 21, 40 which will be driven by means of a belt from some suitable source of power. In the present instance, the belt is illustrated in Fig. 1 by the dotted line 43, and runs over the pulley, similarly indicated in Fig. 1 by 44, which 45 pulley is fast upon the driving shaft 45, having upon it fast and loose pulleys 46, 47.

Mounted upon the slide rest 30 is a slide or carriage 50 which is guided by ways 51 for movement in the line of reciprocation of the 50 slide rest 53. The slide rest is shown as carrying a yoke 52, which receives a screw shaft 53 controlled by a hand wheel 54, and which shaft passes through some suitable bracket 55 in the slide or carriage 50 and is 55 free to move therein, a pair of collars 56 being secured to the shaft upon each side of the portion which passes through the bracket 55. By this means lateral adjustment of all the work-holders may be effected in making the 60 machine ready for operation on different sizes of work and with different sizes of pencils.

Each of the work-holders in the present illustration is supported by a pair of stand-

ards, 76, 77, shown rising from the slide 50, 65 and in which each work-holder is rotatably mounted. Rings 78, 79 are fast in the respective standards 76, 77, and afford ball races for suitable series of balls 80, 81. The body portion 82 of the work-holder is shown 70 as having fast at the front end, that is, the end toward the grinding pencil, a ring 780 constituting the other member of the ball race for that end of the device. At the other end of the body is mounted a ring 83 75 having a free fit upon the body portion. It also forms the other member for the race of balls 81. A ring 84 is fast upon said body portion and forms an abutment for the ring 83 in its longitudinal movement. The ring 80 83 is held against the ring or collar 84 by means of a washer 85 which is pressed in position by means of a series of springs 86 mounted in sockets in a collar 87, which is held to the body portion by means of suitable 85 set screws 88. A pulley 90 having a bearing portion 91 is freely mounted upon the body portion 82, and is held between the collar 84 and the collar 89. Some suitable belt will be run over the pulley 90, and its motion 90 will be communicated to the body of the work-holder by means of some suitable friction clutch when it is desired to rotate the work; and the friction clutch will be released when it is desired to bring the work to a rest. 95 There is also provided a suitable brake for stopping the rotation of the work-holder when the clutch is thrown out. Such clutch in the present instance embodies an engaging member 92 for engaging the face 906 of the 100 pulley, which member is in engagement with a block 93 mounted within the body. The block has grooves 94 upon two of its sides, within each of which there is located a slide block 95 fastened by means of a screw 96 to 105 the clutch member 92. There are also a pair pins 97 working in slots 98 in the block 93 and which pass through slots in the body portion 82 and engage the clutch member 92. Extension springs 99 are interposed between 110 the slide blocks 95 and the head end 100 of the work-holder. This will normally tend to keep the clutch in its clutching or engaged position. For the purpose of withdrawing the clutch, a suitable lever 101 is carried by 115 pivots 102 mounted in lugs 103 of the base of the work head, which lever carries a pair of pins 104 running in a circular groove 105 in the clutch member. The lever may be provided with a suitable handle 106 whereby the 120 clutch member may be moved forward and back as occasion may demand. It will be seen that when the clutch lever 101 is moved so that it will also reciprocate the block 93 through which the pins 97 pass, there will be 125 an amount of free or lost motion between the clutch member and the block 93. Extension springs 110 are mounted within

recesses 111 of the block and tend to press the same forwardly, such springs engaging a ring 112 at the back of the work-holder, which ring is held in place within the body 5 by means of suitable set screws 113. The spring abuts a shoulder 114 for the purpose of pressing the block forward. This is for the purpose of normally tending to open the chuck jaws 115 situated within the slide-ways 116 in the head 100. Each of the chuck jaws has a slanting face 117 which will be engaged by an obliquely disposed jaw operating on arm 118 which is fastened in the present instance by means of a screw 119 to the block 93, so that upon the backward movement of the block with the clutch member, when this is moved into its clutching engagement with the pulley, the jaws will be advanced, and when the clutching member 15 is withdrawn from the pulley the jaws will be drawn from their bottle-engaging position. For the purpose of preventing the arms 118 from spreading apart, a ring 120 may be secured to their forward ends, which not only 20 will prevent their spreading, but act as a front stop and also a steadyng device for the jaws. For the purpose of bringing the work-holder quickly to a rest upon the release of the clutch and of the chuck, a suitable 25 brake may be employed, which in the present instance is shown as a brake-shoe 121 carried by an arm 122 pivoted at 123 at one end of the work-holder and engaging a friction surface carried by a ring or band 124 at 30 the other end. The arm is traversed by an upstanding pin 125 carrying an extension spring 126 which bears upon the arm and upon an abutment in the form of a nut 127. The lower part of the arm 122 is given a cam 35 formation at 128, which cam engages a roll 129 carried by the lever 101, so that when this is in the position to chuck the work and close the friction clutch the brake will be held away from the friction face 124; but 40 upon rocking the lever for withdrawing the clutch members and unclutching the work the arm will be permitted to move responsive to the spring 126 and the spring will be applied to the friction face and quickly 45 bring the work-holder to complete rest.

In the construction illustrated, all the bottles being acted upon will be brought to the working position of the pencil simultaneously, and the work proceeded with until completed, 50 when all the bottles will be moved out of engagement with the grinding pencils and the machine brought to a temporary stop, during which the finished work may be removed and new ones inserted in the chucks.

55 The present means for accomplishing this comprises an abrupt rise or cam face 140, which will by means of the lever 32 and its connections push the slide rest or carriage toward the right in Fig. 2, and bring all the 60 bottles into such a position that the pencil

occupies a central position within the neck and out of contact with any portion of the surface of the bottle. At the same time a belt shipper 141 will be actuated for moving the belt from the fast to the loose pulley, the belt shipper having fast to it a lever 142, which lever has an abutment face 143 for engaging a trigger in the nature of a bell crank lever, it having one portion 144 for engaging the face 143 and an arm 145 for the engagement of a finger or abutment 146 carried by the shift 38. A spring as 147 may be employed for pressing the engaging end 144 of a trigger into engagement with the abutment 143. By this means, after the 65 bottles have been brought to an idle position so far as the grinding is concerned, the belt will be shifted and the rotation of the wheel 37 stopped, so that the attendant may have as long a time as is necessary for 70 the changing of the bottles; when it is again desired to start the mechanism, the handle 147 may be called into use for shifting the belt to its active position. The bottles will be removed by actuating the release mechanism before each work-holder, and the work-holders and the pencil-holders need not be stopped during such change of bottles, except that each work-holder will be stopped during the time that its individual bottle is 75 being changed.

Machines embodying my invention may be made in various forms other than that shown, and with as many or as few glass-cutting pencils and work-holders as may be found convenient. This machine is efficient 80 for grinding the frusto-conical stoppers required, a proper form of stopper-holder being substituted for the bottle-holder.

The machine herein illustrated is one of 85 several forms which may be employed in carrying out my new method of spirally grinding ground glass bottle-necks and ground glass stoppers therefor; and I do not herein claim said method, as it forms the 90 subject-matter of, and is claimed in, my co-pending application Serial No. 385,475, said application also showing my new spirally ground glass bottle-necks and glass stoppers therefor which may be produced by the machine herein described. Said product is claimed in said application Serial No. 385,475. Nor do I claim herein my new glass-grinding 95 pencil, as that forms the subject-matter of, and is claimed in, my co-pending application 100 Serial No. 404,836.

While my invention has been described in 105 relation to the production of interchangeably mated, ground glass bottles and ground glass stoppers therefor, it is also highly useful in the grinding of the joint-forming surfaces of the bottle-necks and stoppers of porcelain and other structures of hardened plastic material.

What I claim is:

1. In a machine for grinding interchangeably mated bottle-necks and stoppers therefor, the combination of a tool-holder; a work-holder; a grinding tool carried by the tool-holder; means for effecting a rotary movement of the grinding tool and work-holder one in relation to the other; means for effecting, during said rotary movement, a reciprocative movement of the tool and work-holder one in relation to the other, in a line at an angle to the axes of rotation of both the tool and work-holder. 10
2. In a machine for grinding interchangeably mated bottle-necks and stoppers therefor, the combination of a pencil-holder; a work-holder; a grinding pencil carried by said pencil-holder and provided with a conical working surface; means for effecting a rotary movement of the pencil and work-holder, one in relation to the other; and means for effecting, during said rotary movement, a reciprocative movement of the pencil and work-holder, one in relation to the other, in a path at an angle to the axes of 20 their rotation; the pencil and work-holder being arranged with their axes of rotation at an angle one to the other; and the conical grinding surface of the pencil being adapted in the operation of the machine, to rotate and to traverse the face of the work being operated on, simultaneously, whereby the correct conical shape of the conical grinding surface and of the work are maintained. 25
3. In a machine for grinding interchangeably mated bottle-necks and stoppers therefor, the combination of a pencil-holder and a work-holder; a grinding pencil carried by said pencil-holder and formed at an end with a conical grinding surface which, with the 30 contiguous surface of the body of the pencil, is so workable that the conical grinding surface is progressively developed throughout the period of use of the pencil; means for effecting a rotary movement of the pencil 35 and work-holder one in relation to the other; means for effecting, during said rotative movement, a reciprocatory movement of the tool and work-holder one in relation to the other; and means for reciprocating said pencil-holder toward and from the work-holder, in a path at a constant angle to the axes of 40 rotation of the work-holder and pencil-holder. 45
4. In a machine for grinding interchangeably mated bottle-necks and stoppers therefor, the combination of a rotatable grinding pencil having a conical grinding surface with a rotatable work-holder; means for rotating the pencil; means for rotating the work-holder; automatic means for reciprocating the 50 pencil and work-holder, one in relation to the other, during their rotary movements, in a line at an angle to their axes of rotation; and means for moving the conical grinding surface of the pencil and the work-holder laterally one in relation to the other, in a path 55 at an angle to their axes of rotation during their rotation. 5
5. In a machine for grinding interchangeably mated bottle-necks and stoppers therefor, the combination, with a rotatable work-holding spindle, of a rotatable tool-spindle; a grinding pencil in said tool-spindle; and means for effecting relative reciprocation between these spindles, in a line at an angle to the axes of their rotation; the working 70 conical end of the pencil being adapted, in the operation of the machine, to rotate and reciprocate, simultaneously, in the plane of the surface of the work being operated upon, whereby the correct conical form of the tool is 75 maintained and the correct conical form of the work is also maintained. 80
6. In a machine for grinding interchangeably mated bottle-necks and stoppers therefor, the combination of a tool-holding spindle with a work-holding spindle; means for bringing said spindles into rotative relations one to another, and means for bringing the spindles to a temporary stop and carrying the spindles out of working relations one to 85 another. 90
7. In a machine for grinding interchangeably mated bottle-necks and stoppers therefor, the combination of a grinding pencil having a conical grinding surface with a work 95 holder, the pencil and work-holder being mounted with their axes of rotation at an angle one to the other; means for effecting rotation of the pencil; means for effecting rotation of the work-holder; automatic means 100 for effecting the reciprocation of the pencil and work-holder one in relation to the other, during the rotative movements thereof, in a line at an angle to their axes of rotation; and means for effecting a feeding movement of 105 the conical grinding surface of the pencil and of the work-holder, one in relation to the other, in a path which is at a constant angle to their axes of rotation. 110
8. In a machine for grinding interchangeably mated bottle-necks and stoppers therefor, the combination with a grinding pencil having a conical grinding surface and means for reciprocating the same; of a work-holder; means for carrying the work-holder and embodying a slide and slide-rest, each movable transversely of the path of reciprocation of the pencil; means for reciprocating said slide-rest; and means for adjusting the position of the slide upon the slide-rest. 115 120
9. In a machine for grinding interchangeably mated bottle-necks and stoppers therefor; the combination with a slide; means for reciprocating the same; a series of rotary tool-spindles carried thereby; a transversely reciprocating slide; a series of work-holders carried thereby; a cam having faces for reciprocating said work-holder slide for bringing all the work quickly into working engagement with the tools and for quickly return- 125 130

ing the slide for moving all the work out of working engagement with the tools.

10. In a machine for grinding interchangeably mated bottle-necks and stoppers therefor, the combination with a rotary work-holder of rotary means for holding a grinding pencil having a conical grinding surface; means for reciprocating the conical grinding surface of the pencil across and in uniform contact with the face of the work held in the work-holder, in a fixed path at an angle to the axes of rotation of the work-holder and pencil.

11. In a machine for grinding interchangeably mated bottle-necks and stoppers therefor, the combination with a rotary work-holder of rotary means for holding a grinding tool; means for reciprocating the grinding tool across the surface and in uniform contact with the face of the work held in the work-holder, in a path at an angle to the axes of rotation of the work-holder and pencil; and means for effecting a feeding movement of the grinding tool and work-holder, one in relation to the other, during the reciprocation of the conical grinding surface across the face of the work.

12. In a machine for grinding interchangeably mated bottle-necks and stoppers therefor, the combination with a work-holder of a rotary tool-spindle; means for reciprocating said spindle toward and from the work-holder in a path at a constant angle to the axes of rotation of the work-holder and tool-spindle; an abrasive pencil in said spindle, and means for moving the work laterally into and out of the working zone of the pencil.

13. In a machine for grinding interchangeably mated bottle-necks and stoppers therefor, the combination of a work-holding spindle with work-clamping jaws carried thereby; a clutch for rotating said spindle; means for controlling said clutch and jaws; a brake for engaging the spindle to stop the same; and means for drawing the brake out of engagement with the spindle when in the jaw-clamping and clutch-operating position.

14. In a machine for grinding interchangeably mated bottle-necks and stoppers therefor, the combination of a work-holding spindle with clamping jaws carried thereby; a clutch for rotating said spindle; means for controlling said clutch and jaws; a spring-pressed brake for engaging the spindle to stop the same; and means for drawing the brake out of engagement with the spindle when in the jaw-clamping and clutch-operating position.

15. In a machine for grinding interchangeably mated bottle-necks and stoppers therefor, the combination with a grinding tool and means for actuating the same, of a work-holder adjacent thereto and embody-

ing means for clamping the work, means for rotating the work-holder, and also embodying a friction clutch and means for actuating the friction clutch and work-holder.

16. In a machine for grinding interchangeably mated bottle-necks and stoppers therefor, the combination with a grinding pencil of a work-holder comprising a body portion; bearings for the same, one of which bearings is floating and spring-pressed; a pulley loose upon said body and having a clutch-engaging face; a clutch member; a block mounted within said body portion; radially sliding jaws carried by the said block; a clutch engaging said block; means for advancing the clutch member into engagement with said pulley; springs normally tending to force said block and fingers into the opening position of the same, and means normally tending to close the clutch.

17. In a machine for grinding interchangeably mated bottle-necks and stoppers therefor, the combination with a grinding tool of a work-holder chuck comprising a body portion; bearings for the same, one of which bearings is floating and spring-pressed; a pulley loose upon said body and having a clutch-engaging face; a clutch member; a block mounted within said body portion; radially sliding jaws carried by the body; jaw-engaging fingers carried by said block; a clutch engaging said block; means for advancing the clutch member into engagement with said pulley; springs normally tending to force said block and fingers into the opening position of the same; means normally tending to close the clutch; a brake for engaging a portion of the spindle for stopping the rotation of the same and controlled by the clutch and jaw-controlling mechanism.

18. In a machine for grinding interchangeably mated bottle-necks and stoppers therefor, the combination with a grinding pencil and means for actuating the same, of a work-holding spindle adjacent thereto and embodying means for clamping the work; means for rotating the spindle and embodying a clutch and means for concurrently actuating the clutch and the work-clamping means.

19. In a machine for grinding interchangeably mated bottle-necks and stoppers therefor, the combination with a grinding tool of a work-holding chuck comprising a body portion; a pulley loose upon said body and having a clutch-engaging face; a clutch member; a block mounted within said body portion; radially sliding jaws carried by the body; jaw-engaging fingers carried by said block; means of connection between the clutch and said block; means for advancing the clutch member into engagement with said pulley; means normally tending to

force said fingers into an open position; and means normally tending to close the clutch.

20. In a machine for grinding interchangeably mated bottle-necks and stoppers therefor, the combination with a grinding device of a work-holding spindle; a clutch for rotating the same; a lever for controlling said clutch; a brake for stopping the rotation

of said spindle and controlled by the clutch-operating lever.

Signed at Nos. 9-15 Murray street, New York, N. Y. this 11th day of May, 1906.

CONRAD M. CONRADSON.
